ANDREAS BING, OF WESERMUNDE, GERMANY

SPRINGING FOR UPHOLSTERY

Application filed May 28, 1929, Serial No. 366,596, and in Germany June 2, 1928.

This invention relates to a wire spring for cushion seats and aims to provide a construction which dispenses with the use of webbing and a form which is laterally undulated in 5 such manner that it is shiftable longitudinally on the chair frame.

An object is to provide an exceedingly simple and inexpensive construction wherein the spring which bears against the cushion 10 is shiftable against the variable friction of an end fastening or fastenings. This construction presents the advantage that during the bending of the spring with the cushion, its tension remains almost constant so that 15 the cushioning is much softer and an intermittent counter pressure cannot occur. Such a construction is also greatly simplified and inexpensive especially when produced in quantities, since for fastening the spring 20 carrying the cushion, merely a hinge is required at one end and an eye mounting is used at the other end.

The invention is intended for use with all kinds of upholstery, primarily for chairs. 25 By the use of the new springing not only the objections to the former upholstery are avoided but the use of webbing is rendered absolutely unnecessary.

The invention is illustrated by way of 30 example in the accompanying drawings in which

Fig. 1 shows a cross-section through the seat of a chair.

Fig. 2 is a top plan view of the spring *c*. 35 In the drawings,

a is the chair seat frame, *b* the upholstery and *c* the spring which is secured at one end in a clamp or hinge *d* which is fastened to the seat frame by a number of staples. The other 40 end of the spring is held by a clamp *e* which is also fastened to the seat frame *a*.

As shown in Fig. 2 the spring is composed of spring bars *f* and *g* bent laterally in zigzag shape and fastened in the clamps *d* and *e*. 45 The spring bars *f* and *g* are held together by means of clamps *h*. Either two individual spring bars *f* and *g* or a continuous wire spring having its free ends inserted in the clamp *d* may be used. One or both of the 50 clamps *d* and *e* has a slot *i*, in which the spring

c is capable of slight displacement. In order to prevent noise this slot *i* may be provided with a strip of leather. The spring in its normal position assumes the upwardly bowed shape shown in Fig. 1.

One feature of the invention resides in the fact that this novel form of spring rests throughout almost its whole length on the seat and is fully utilized for carrying the load, and thereby the pressure is uniformly distributed, whereas with the ordinary cylindrical springs only single points are supported and with flat spiral springs only some of the springs carry the load. A further important advantage of the springs is the fact that the arrangement of the springs in the desired manner, i. e. domed, ensures the good shape of the seat.

It will be noted that the eye *e*, in which the spiral spring *f*, *g* or *c*, respectively, can slide longitudinally is not situated in its normal position in the direction of the curvature of the spring, but is at an angle of about 20° or 30° thereto. By this arrangement, in the event of a slight loading of the cushion, the individual lateral portions of the spring *f*, *g* are pressed together, but a longitudinal shifting of the spring in the eye *e* does not at first take place because the curved spring acts on an incline from above on the lower surface of the eye and is held back by the friction resulting therefrom. Only when the tension of the spring *f*, *g* has further increased and at the same time the inclination angle of the curvature of the spring *f*, *g* or *c* relative to the direction of the eye *e* has reduced, that is has become practically zero, the one sided friction in the eye disappears and consequently the spring *f*, *g* can then shift longitudinally.

By the construction described the tension of the spring will remain practically constant during its entire bending and the cushioning will therefore be soft and neither a sudden sagging nor an intermittent counter pressure can occur.

An advantage of the springs according to the invention is that they are extremely simple to make and secure and can be advantageously packed. A point worthy of

particular mention is the fact that the springs may be used without any accessories, that is to say, without the use of webbings, coverings or similar arrangements, so that 5. their fitting is extremely simple. Instead of the surrounding clamps ordinary wire clamps may be used. The individual springs may be arranged side by side either parallel or at any desired angle the one to the other.

10 I claim:

1. A spring for spring seats comprising an upwardly convex spring element adapted for supporting contact with a cushion, said spring being a wire generally of U-shape and 15 having lateral undulations, a mounting member, the terminals of said wire being pivotally engaged in said mounting member, a second mounting member, said second mounting member having an elongated slot through 20 which the wire passes, said elongated slot permitting longitudinal shifting of said wire when yielding of the undulations is insufficient to accommodate the load.

2. A spring according to claim 1 wherein 25 said spring wire is in a single piece.

3. A spring according to claim 1 wherein that portion of the wire passing through the second mentioned mounting member is the connecting member for the arms of the 30 spring, said connecting portion as it slides causing one spring arm to take up the longitudinal load on the other spring arm.

4. A spring for spring seats comprising an upwardly convex spring element adapted for 35 supporting contact with a cushion, said spring being generally endless and having substantially parallel arms and first and second connecting portions, said arms having lateral undulations, mounting members having 40 openings in which said first and second connecting portions are pivoted, said mounting members being disposed in rigid relation, one of said mounting members having its 45 opening elongated to permit longitudinal shifting of said spring when yielding of the undulations is insufficient to accommodate the load, said portions being adapted for increase of frictional engagement with the mounting members under a load.

50 In testimony whereof I affix my signature.
ANDREAS BING.
